UNITED STATES PATENT OFFICE.

THOMAS H. HOADLEY, OF GLADBROOK, IOWA.

RAILROAD-TIE.

1,116,275.

Specification of Letters Patent.

Patented Nov. 3, 1914.

Application filed August 21, 1914. Serial No. 857,896.

To all whom it may concern:

Be it known that I, THOMAS H. HOADLEY, a citizen of the United States, residing at Gladbrook, in the county of Tama and State 5 of Iowa, have invented certain new and useful Improvements in Railroad-Ties; and I do hereby declare the following to be a full, clear, and exact description of the invention, such as will enable others skilled 10 in the art to which it appertains to make and use the same.

My invention relates to new and useful improvements in metallic rail ties and has for its primary object to generally improve 15 and simplify the construction of such devices so as to render them more reliable and efficient in supporting rails, inexpensive to manufacture and durable.

An object of importance is to provide a 20 rail tie of the character described that possesses the resiliency of a wooden tie in combination with the durability and other indestructible properties of the metallic tie.

The above and additional objects are accomplished by such means as are illustrated 25 in the accompanying drawings, described in the following specification and then more particularly pointed out as claimed.

With reference to the drawings, wherein 30 I have illustrated the preferred embodiment of my invention as it is reduced to practice and throughout the several views of which similar reference numerals designate corresponding parts,

Figure 1 is a perspective view of my improved tie with the rails removed. Fig. 2 is a fragmentary longitudinal sectional view taken through one of my ties showing the rail in position. Fig. 3 is a transverse section 35 view taken through the tie at a point adjacent to one end, and Fig. 4 is a detailed perspective view of one of the wedge plates.

Referring to the drawings 1 designates as an entirety a metallic base plate of the 45 tie which is provided upon its longitudinal edges with upwardly and inwardly inclined sides 2 which sides extend the full length of the plate 1 and adjacent to each end are recessed as at 3 for a purpose to be later 50 more fully described.

Mounted between the side walls 2 at the end of the tie are wedge shaped or dove-tail rail supporting blocks 4 which are formed of wood or some other suitable resilient material and of just sufficient size to adequately 55 support the rails. The rail bases are de-

signed to engage upon blocks 4 at points where the recesses 3 are formed so that the rails will be allowed to sink without engaging the sides 2. To hold the blocks 4 against outward horizontal displacement 60 bolts 4^a are provided. These bolts pass through the side 2 and engage the inner ends of the blocks 4.

Adjacent each end of the tie is formed a 65 pair of transverse rectangular holding straps 5 and 5^a. The straps 5 are formed integral with the sides 2 and engage upon the upper faces of the blocks 4. These straps are sufficiently spaced to permit the rails to 70 be placed upon the blocks 4 between the straps and to have the spikes 6 for securing the rails inserted between the bases of the rails and the straps.

A filler or body of concrete 7 or some 75 other suitable plastic material is placed within the tie between the opposed inner ends of the blocks 4 and said filler of concrete or the like has its upper face flush with the sides of the tie. The filler 7 is 80 reinforced by rods 7^a which are embedded therein and which extend longitudinally thereof. The straps 5^a extend inwardly beyond the inner ends of the blocks 4 so as to overlie the filler 7 and thereby prevent it 85 from having any vertical movement with relation to the tie. At points intermediate the straps 5^a the tie is provided with straps 7^b which also prevent the filler from having any vertical movement with relation to 90 the tie. Should the blocks 4 become loose as a result of shrinkage or wear, they may be tightened up by means of the wedge plates 8. In practice the wedge plates 8 are inserted beneath the blocks 4, bringing 95 their sides in firm engagement with the inner surfaces of the sides 2 and their tops in firm engagement with the under sides of the straps 5 and 5^a. The blocks 4 are prevented upward longitudinal and lateral 100 movement by the side walls 2 and the particular arrangement of the straps 5.

It will be readily seen that my improved rail tie will prove extremely durable and provides for a great amount of track resiliency. The parts are of similar construction and may be readily assembled and disassembled for renewal if desired.

In practice, I have found that the form of my invention, illustrated in the drawings 110 and referred to in the above description, as the preferred embodiment, is the most

efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as set forth.

10 10 What is claimed is:—

- 11 11 1. A rail tie consisting of a base plate, upstanding inwardly inclined side walls on the base plate, resilient rail supporting blocks mounted within the ends of the base plate between the side walls and being dovetailed to coöperate with the inclined side walls, and supporting straps engaging the tops of the blocks and formed integral with the sides.
- 12 12 2. A rail tie consisting of a rectangular base plate, upstanding inwardly inclined side walls formed on the longitudinal edges of the base plates, resilient rail supporting blocks mounted upon the base plate between the side walls and having upwardly and inwardly inclined side faces to coöperate with the side walls, straps formed integral with the side walls adjacent to each end and arranged in pairs and extending transversely of the tie in engagement with the tops of the rail supporting blocks and being spaced from one another, and a plastic filler mounted between the side walls and inner ends of the blocks, said side walls being recessed at their upper edges at points between said straps.
- 13 13 3. A rail tie consisting of a rectangular base plate, upstanding inwardly inclined side walls formed on the longitudinal edges of the base plate, resilient rail supporting blocks mounted within the ends of the base plate between the side walls and being dovetailed to coöperate with the inclined side walls, and supporting straps engaging the tops of the blocks and formed integral with the sides.

14 14 tops of the rail supporting blocks and being spaced from one another, a plastic filler mounted between the side walls and inner ends of the blocks, and said side walls being recessed at their upper edges at points 35 between said straps.

15 15 3. A rail tie consisting of a rectangular base plate, upstanding inwardly inclined side walls formed on the longitudinal edges of the base plate, resilient rail supporting 40 blocks mounted upon the base plate between the side walls and having upwardly and inwardly inclined side faces to coöperate with the side walls, straps formed integral with the side walls adjacent to each end and 45 arranged in pairs and extending transversely of the tie in engagement with the tops of the rail supporting blocks and being spaced from one another, and a plastic filler mounted between the side walls and inner 50 ends of the blocks, said side walls being recessed at their upper edges at points between said straps.

In testimony whereof I affix my signature in presence of two witnesses.

THOMAS H. HOADLEY.
